SLIDING DOOR

Harold F. Collins, Rockford, Ill., assignor to
Howard D. Colman, Rockford, Ill.

Application February 6, 1930, Serial No. 426,216

21 Claims. (Cl. 20—20)

The invention pertains to doors of the sliding type, consisting of one or more panels guided for edgewise movement from a position in closing relation to a door opening, into an open position 5 at one side of the opening.

The primary object of the invention is to provide improved means for guiding the door from open to closed position and vice versa, of a character such that the door in moving into 10 closed position automatically assumes a tightly fitting relation to the door frame without resulting, as a necessary incident, in a binding or wedging action such as to interfere with the easy movement of the door away from its closed position.

A further object is to provide a combined guiding and control means for a door of the character referred to, which insures a free edgewise movement of the door toward and from closed position, and additionally acts upon the door as it approaches or leaves such position to effect an abrupt change in the direction of movement, imparting thereto a bodily movement carrying its marginal edge portions in tightly fitting relation to the door frame.

Another object is to provide a guiding and control means of the character referred to which is adapted for use in connection with doors composed of a series of panels hinged together in 30 abutting edge relation.

A general object is to provide a door guiding means of the character referred to which is capable of economical manufacture and which is positive in operation and otherwise of a practical character.

In the accompanying drawings I have illustrated the invention in its preferred form, as applied to a door of the overhead type. In these drawings:

Figure 1 is a fragmentary elevational view of an overhead multipanel door in its closed position and showing the rear side of the door.

Fig. 2 is a fragmentary vertical sectional view on a somewhat larger scale, the view being taken 45 substantially in the plane of line 2—2 of Fig. 1.

Fig. 3 is a fragmentary vertical sectional view showing the upper panel of the door in a position occupied during the movement from horizontal to vertical position.

Fig. 4 is a similar view but showing the upper portion of the door in closed position.

Fig. 5 is a fragmentary perspective view illustrating the guiding and control means employed.

Fig. 6 is a fragmentary sectional view illustrating the counterbalancing means.

The door as shown comprises a plurality of panels 7 hinged together in abutting edge to edge relation, the number and size of the panels being determined by the size of the opening to be closed. The latter is herein shown as formed by a frame 8 providing an abutment 9 against which marginal edge portions of the door engage in the closed position of the door. Any suitable form of hinge connections may be provided, but preferably consist of hinge members or plates 10 and 11 (Fig. 5), the plate 10 having side flanges 12 to form bearings for a hinge pin 13, and the plate 11 having a curl 14 for receiving the pin between the bearing flanges 12.

The panels 7 thus hinged together are guided 15 for edgewise movement from a vertical position closing the door opening into an overhead, substantially horizontal position, by means comprising a pair of tracks 15 one for each side edge of the door, and two sets of rollers 16, the rollers of the 20 two sets being carried by the door and engaging respectively in the opposite tracks 15.

The tracks consist of straight vertical sections 17, straight horizontal sections 18, and intermediate curved sections 19. The straight vertical 25 sections 17 are suitably secured to the door frame as by means of brackets 20, and herein are spaced inwardly from the frame abutment 9 a distance substantially greater than the thickness of the panels. The upper rear end of the straight horizontal sections 18 of each track may be suspended 30 from a suitable overhead support as by means of a bracket 21.

The guide rollers 16 are supported in pivotal relation to the door panels and are made of a 35 diameter substantially corresponding to the width of the guiding channel provided by the tracks 15. In the present instance the pivotal supports for the rollers 16 are in the nature of triangularly shaped arms. The uppermost arms 22, owing to the fact that the rollers carried thereby engage with the curved sections 19 of the tracks in the closed position of the door, are made somewhat longer than the other arms 23 engaging the straight vertical sections of the tracks.

Each of said arms 22 and 23 is made rigid with one end of a hinge pin 13, and in each instance the opposite end of the pin 13 is extended to receive a coiled spring 24, one end of which is anchored to the pin through the medium of 50 a collar 25 and the other end 26 is extended upwardly so as to bear against the adjacent panel. Thus the arms 23 are normally urged by their springs 24 in a direction to swing the rollers 16 downwardly with the result that the springs nor-

mally serve to hold the panels inwardly away from the door opening and hence free of the frame abutment 9. In this connection, the arms 22, 23 because of their peculiar triangular shape, coact 5 with the lowermost hinge plates 10 to limit the extent of movement of the panels toward the tracks.

While it is desirable that the door be capable of free sliding movement, it is also desirable that when in closed positon its marginal edge portions 10 be held in tightly fitting relation to the frame abutment 9. To this end the several arms 22 and 23 are interconnected by links 27, and inward extensions 28 of the uppermost arms 22 carry stop pins 29 adapted to engage with stationary 15 stops 30 just as the door approaches its closed position. The links 27 have pin-and-slot connections 27a at their lower ends with the arms 23 in order to permit of relative lengthwise movement between the links as the door panels swing 20 relative to each other in passing from vertical to overhead horizontal position, and vice versa.

The arrangement is such (compare Figs. 3 and 4) that in the movement of the door into closed 25 position, the pins 29 on the upper arms 22 strike the stop 30, and in the continued movement of the panels toward closed position the uppermost panel swings forwardly toward the frame abutment 9. Then in the final relatively short closing 30 movement of the door, all of the rollers 16 are simultaneously interrupted, causing the arms 22, 23 to rock downwardly and forwardly and, with a toggle-like action, impart a relatively sudden forward movement to the panels at their 35 several hinge connections. The result is that all of the panels are simultaneously carried into snugly fitting relation to the frame abutment, against the action of the springs 24. In the closed position of the door, as shown in Figs. 2 40 and 4, the axes of the rollers 16 and of the corresponding hinge pins 13 are disposed in substantially the same horizontal plane.

When the door is moved away from closed position, the arms 22 and 23 turn relative to the 45 panels, the rollers being held downwardly by the action of the springs 24 so that the panels are immediately moved inwardly away from the frame abutment 9, permitting free continued movement into open position.

To facilitate the operation of the door, a counterbalancing means is preferably provided. The means herein shown for this purpose comprises 50 a pair of springs, one for each side edge of the door. Said springs are in the form of torsion 55 springs 31, each coiled about a drum 32 and connected at one end to a stationary plate 33, and at its other end to a sheave 34, the whole being supported from a bracket 35. A small wire cable 36 is anchored at one end to the sheave 33 and at 60 its other end to the lower end of the door, the springs being under maximum tension when the door is in its closed position.

I have found that the construction provided insures that the door, when in closed position, 65 will be held against the frame or other abutment with the desired degree of snugness, and since this result is accomplished by the use of pivotal elements having a definite predetermined range of movement, I avoid the tendency heretofore experienced with other doors to stick or bind to an extent such as to render their operation from closed position very difficult. Moreover, the construction employed will be seen to be of a rugged 70 character and capable of manufacture at relatively low cost.

I claim as my invention:

1. The combination of a door having a plurality of panels hinged together in edge to edge relation, a door frame providing an opening with an abutment for engagement by marginal edge portions of the panels, a plurality of actuating elements pivotally mounted on the door panels, and a track engaged by said elements to guide the door in a plane approximately parallel to the door opening, said elements being swingable relative to the individual panels as the door approaches or leaves its closed position to impart to the individual panels a relatively abrupt movement toward or from the plane of the door opening whereby to carry said marginal edge portions toward or from said abutment. 10 15

2. The combination of a door, a door frame providing an opening with an abutment for engagement by marginal edge portions of the door, said door being movable edgewise across said opening, and guiding and controlling means for the door including a plurality of pivotal actuating elements carried by the door, said elements being swingable relative to the door as it approaches its closed position to impart thereto a relatively abrupt movement toward the plane of the door opening whereby to carry said marginal edge portions against said abutment, and spring means operable in the movement of the door away from its closed position to move it abruptly in a direction away from the abutment. 20 25 30

3. A door having marginal edge portions adapted to engage with a door frame to close the opening therethrough, guide means extending substantially parallel to the door opening, a plurality of crank arms pivoted to said door at points spaced apart in the direction of travel of the door, means in said arms engaging with said guide means, and means operating as the door approaches or leaves its closed position to impart a turning movement to each of said crank arms to produce an arcuate motion of the ends connected to the door whereby to impart to the latter a relatively abrupt movement toward or from said frame. 40 45

4. The combination with a door frame, of a door having marginal edge portions adapted to engage said frame and movable in a plane parallel to the frame into and out of closed relation thereto, a pair of crank arms pivoted to the door at points spaced apart in the direction of its movement, a track spaced from the door on the side opposite the frame and extending in a direction substantially parallel to the frame, guiding elements carried by the crank arms and adapted to engage said track at spaced points, and means operable as an incident to the edgewise movement of the door in approaching its closed position to impart a turning movement to each of said arms and thereby effect a relatively abrupt movement of the door toward the frame. 50 55 60

5. The combination with a door frame, of a door having marginal edge portions adapted to engage said frame and movable in a plane substantially parallel to the frame into and out of closed relation thereto, a pair of crank arms pivoted to the door and having limited rotational movement relative thereto, a track spaced from the door on the side opposite the frame and extending in a direction substantially parallel to the frame, guiding elements carried by the crank arm and adapted to engage said track, means operable as an incident to the edgewise movement of the door in approaching its closed posi- 70 75 80 85 90 95

tion to impart a turning movement to each of said arms and thereby effect a relatively abrupt movement of the door toward the frame, and spring means acting to rotate said arms reversely as an 5 incident to the edgewise movement of the door away from said closed position and thereby carry the marginal edge portions laterally away from the frame.

6. The combination with a door frame of a 10 door having marginal edge portions arranged to abut said frame and movable edgewise relative to the frame in opening and closing the door, a track spaced from the frame, a crank arm pivoted at one end to the door and having a guide 15 element engaging in said track, spring means acting between said door and said arm and tending to rotate the arm in a direction to move the door laterally away from the frame, and stop means acting upon said arm in the approach of 20 the door into its closed position to rotate the arm against the action of said spring means and in a direction to move the door laterally against said frame.

7. The combination with a door frame of a 25 door having marginal edge portions arranged to abut said frame and movable edgewise relative to the frame in opening and closing the door, a track spaced from the frame, a pair of crank arms pivoted at one end to the door and having guide elements engaging in said track, spring means acting between said door and said arms and tending to rotate the arms in a direction to move the door laterally away from the frame, and stop means acting upon said arms in the 30 approach of the door into its closed position to rotate the arms against the action of said spring means and in a direction to move the door laterally against said frame, said stop means including a stop member mounted in fixed relation to the track and adapted for engagement by one of said arms as the door approaches its closed position, and a link connecting the two arms.

8. The combination with a door frame, of a 45 door having marginal edge portions arranged to abut said frame and movable edgewise relative to the frame in opening and closing the door, a track spaced from the frame, a pair of crank arms pivoted at one end to the door and having guide elements engaging said track, spring means acting between said door and said arms and tending to rotate the arms in a direction to move the door laterally away from the frame, and stop means acting upon said arms in the 50 approach of the door into its closed position to rotate the arms against the action of said spring means and in a direction to move the door laterally against said frame, said arms having parts adapted to engage with the door to limit their 55 rotational movement under the action of said spring means.

9. The combination of a door frame, a door 65 comprising a plurality of panels hinged together in abutting edge relation, a pair of tracks at opposite sides of the door opening with relatively straight vertical sections parallel to the door opening, straight horizontal sections above the door opening, and curved sections connecting the straight sections, a plurality of crank arms each 70 having one end pivotally connected to the door, rollers carried by the arms and engaging in said tracks, links connecting the several crank arms at each side of the door, said links being adapted to permit relative turning movement between 75 the panels as the door moves from its vertical

position into overhead position or vice versa, and stop means operating as an incident to the movement of the door into closed position to rock the interconnected arms in a direction to move the panels laterally into tightly fitting relation 5 to the frame.

10. The combination of a door frame, a door comprising a plurality of panels hinged together in abutting edge relation, a pair of tracks at opposite sides of the door opening with relatively straight vertical sections parallel to the door opening, straight horizontal sections above the door opening, and curved sections connecting the straight sections, a plurality of crank arms each having one end pivotally connected to the door, rollers carried by the arms and engaging in said tracks, links connecting the several crank arms at each side of the door, said links being adapted to permit relative turning movement between the panels as the door moves from its 20 vertical position into overhead position or vice versa, and stop means operating as an incident to the movement of the door into closed position to rock the interconnected arms in a direction to move the panels laterally into tightly fitting relation 25 to the frame, said stop means including a pair of stop members adjacent the upper edge of the door opening, and parts carried by the uppermost arms at opposite sides of the door and adapted to engage said stop members as the door approaches its closed position.

11. The combination of a door frame providing an opening with a marginal abutment, a door having a plurality of panels with marginal edge portions adapted to engage said abutment, 35 hinges connecting said panels in edge to edge relation and each including a hinge pin, a track, an arm fast on each hinge pin and having a guide element engaging said track, springs mounted on said hinge pins and acting upon the 40 door, said springs tending to rotate said arms in a direction to move the door away from the abutment, and means operable as the door moves into closed position to rock said arms against the action of said springs. 45

12. The combination of a door frame providing an opening with a marginal abutment, a door having a plurality of panels with marginal edge portions adapted to engage said abutment, 50 hinges connecting said panels in edge to edge relation and each including a hinge pin, a track, an arm fast on each hinge pin and having a guide element engaging said track, springs mounted on said hinge pins and acting upon the door, said springs tending to rotate said arms in a direction to move the door away from the abutment, and means operable as the door moves into closed position to rock said arms against the action of said springs, each of said arms having parts 55 cooperating with the door to limit their rotational movements by their respective springs. 60

13. A door comprising a plurality of panels having hinges connecting them in edge to edge relation, guide means including a track adapted to be mounted in substantially parallel relation 65 to a door opening, swingable arms carried by the hinges between adjacent panels and having rollers on their free ends adapted to engage with said track, and means operable as the door moves into its closed position to swing said arms simultaneously in a direction to force said panels into tightly fitting relation to the door opening. 70

14. In an overhead door construction, a plurality of hingedly connected shiftable door members for traversing a door opening, guiding 75

- means for directing the movements of said door members between open and closed positions, said guiding means including an upright section, and door closing means shiftably and solely supported by the door members at the hinged connection thereof, said means being adapted when shifted with respect to the door members to effect lateral movement thereof toward the door opening.
10. 15. In an overhead door construction, a plurality of shiftable door members for traversing a door opening, guiding means for directing the movements of said door members between open and closed positions, said guiding means including an upright section, door closing means shiftably supported by the door members, said means being adapted when shifted with respect to the door member to effect lateral movement thereof toward the door opening, and means for automatically effecting the shifting of said door closing means when the door members are shifted to a predetermined position.
15. 16. The combination of a door having a plurality of hingedly connected panels, a door frame providing an opening with an abutment adapted for engagement by the door in the closed position thereof, means for directing the movements of the door edgewise between a closed upright position and a substantially horizontal position near one edge of the door opening, said means including a guide track and a plurality of arms pivotally supported by the door adjacent the hinge connections between said panels and having guide elements at their free ends engaging in said track and disposed below the arm pivots while the door is moving in a vertical direction, and actuating means operating automatically as an incident to the movement of the door into closed position to swing the arms so as to carry said guide elements upwardly, said elements operating in such movement to exert a thrust between said track and the door so as to impart a relatively abrupt movement to the door in a direction toward said frame.
20. 17. An overhead door having a plurality of hingedly connected panels for traversing an opening, tracks having upright sections adjacent the opening and substantially horizontal sections receding from the opening, a plurality of closing elements shiftably and solely supported by the door panels at the hinged connection thereof, and actuating means operable automatically as an incident to the movement of the door into closed position to shift said elements relative to the door, said elements operating when thus shifted to effect an abrupt lateral movement of the door panels toward the door opening.
25. 18. An overhead door having a plurality of hingedly connected panels for traversing an opening, tracks having upright sections adjacent the opening and substantially horizontal sections receding from the opening, a plurality of closing elements shiftably and solely supported by the door panels at the hinged connections therebetween, actuating means operable automatically as an incident to the movement of the door into closed position to shift said elements
- relative to the door, said means including a stop, a device adapted to engage with the stop as the door moves into its closed position and having a part movable upwardly upon such engagement, and means connecting said elements for movement in unison by said upwardly moving part, said connecting means being constructed to permit said panels to swing relative to each other in passing from said receding section to said upright section and vice versa.
30. 19. An overhead door having a plurality of hingedly connected panels for traversing a door opening, tracks having upright sections spaced inwardly a short distance from the door opening and substantially horizontal sections receding from the door opening, a plurality of arms pivotally supported by the door panels at the hinged connections therebetween and having guide elements engaging in said tracks, links connecting said arms at points spaced from their pivots, an actuating device, and a stop adapted to be engaged by said device as the door moves into its closed position, said device operating upon engagement with said stop to impart a swinging movement to all of said arms and said arms operating in such movement to cause the door to move laterally toward the door opening, said links having a lost motion connection so as to permit the door panels to swing relative to each other in passing from said receding section to said upright section and vice versa.
35. 20. An overhead door having a plurality of hingedly connected panels for traversing an opening, tracks having upright sections adjacent the opening and substantially horizontal sections receding from the opening, a plurality of closing elements shiftably and solely supported by the door panels at the hinged connections therebetween, actuating means operable automatically as an incident to the movement of the door into closed position to shift said elements relative to the door, said means including a stop, a device adapted to engage with the stop as the door moves into its closed position and having a part movable upwardly upon such engagement, and means connecting said elements for movement in unison by said upwardly moving part, said device also being operable upon the uppermost panel to move its upper edge toward the door opening.
40. 21. The combination of a door frame, a door comprising a plurality of panels hinged together in abutting edge relation, a pair of tracks at opposite sides of the door opening with relatively straight vertical sections parallel to the door opening, straight horizontal sections above the door opening, and curved sections connecting the straight sections, a plurality of arms each having one end pivotally connected to the door for limited movement relative thereto, guide elements carried by the arms and engaging in said tracks, means connecting the several arms at each side of the door, and stop means operating as an incident to the movement of the door into closed position to rock the interconnected arms in a direction to move the panels laterally into tightly fitting relation to the frame.
